CLAIM

The ornamental design for a dental composite shade guide, as shown and described.

DESCRIPTION

FIG. 1 is a perspective view of a dental composite shade guide;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The even-length broken lines in the figures are for illustrative purposes only, showing portions of the dental composite

(Continued)

shade guide that form no part of the claimed design. The dot-dashed lines show the bounds of the claimed design and form no part thereof.

1 Claim, 3 Drawing Sheets
